(57) **CLAIM**

The ornamental design for a hair styling device, as shown and described.

DESCRIPTION

1. Hair styling device
2. Hair styling device

FIG. 1.1 is a perspective view of a first embodiment of a hair styling device showing the new design;

FIG. 1.2 is a top view thereof;

FIG. 1.3 is a bottom view thereof;

FIG. 1.4 is a right view thereof;

FIG. 1.5 is a front view thereof;

FIG. 1.6 is a back view thereof;

FIG. 1.7 is an open perspective view thereof;

FIG. 1.8 is a left view thereof;

FIG. 1.9 is a right open view thereof; and

FIG. 1.10 is a left open view thereof.

FIG. 2. is a perspective view of a second embodiment of a hair styling device showing the new design;

FIG. 2.2 is a top view thereof;

FIG. 2.3 is a bottom view thereof;

FIG. 2.4 is a right view thereof;

FIG. 2.5 is a front view thereof;

FIG. 2.6 is a back view thereof;

FIG. 2.7 is an open perspective view thereof;

(Continued)

FIG. 2.8 is a left view thereof;
FIG. 2.9 is a right open view thereof; and
FIG. 2.10 is a left open view thereof.
The broken lines illustrate portions of the hair styling device
that form no part of the claimed design.
